UNITED STATES PATENT OFFICE

2,197,911

CENTRIFUGAL SEPARATOR

Gustav Harry Andersson, Appelviken, Sweden,
assignor to The De Laval Separator Company,
New York, N. Y., a corporation of New Jersey

Application September 9, 1937, Serial No. 162,986
In Germany October 17, 1936

1 Claim. (Cl. 233—22)

This invention relates to centrifugal separators in which the lighter liquid is discharged by a stationary paring device projecting into the bowl during operation.

5 In centrifugal separators of this type it has been customary to use an open outlet for the heavier liquid, which outlet is located below the chamber containing the paring device. The outlet in this case is through an opening which can be regulated by a screw or the like.

For certain purposes, however, it is desirable to use an outlet in the form of a level outlet, the radius of the free surface of liquid determined thereby being controlled by an exchangeable so-called regulating disc. It is, of course, possible to arrange such a regulating disc below the parer chamber, i. e., between this chamber and the separating chamber. In such a case, however, either the inner diameter of the disc 10 must be so great that the disc can be put in place over the outer wall of the parer chamber, or the parer chamber must be detachably secured to the centrifugal bowl. And since the radius of the liquid surface is determined by the 15 diameter of the outlet in the regulating disc, the first alternative results in unnecessarily great power consumption; while the second alternative presents an exceedingly difficult and troublesome problem from the standpoint of manufacture and operation.

In accordance with the invention, these difficulties are avoided by providing a level outlet for the heavier liquid above the parer chamber and thus axially outside the paring discharge device.

35 The accompanying drawing shows several embodiments of the invention.

Fig. 1 is a fragmentary section view through a centrifugal separator designed in accordance with this invention; and

40 Fig. 2 is a detail sectional view showing a modified type of outlet for heavier liquid.

Referring to Fig. 1, the paring device comprises a parer disc 1, enclosed by a paring chamber 2 arranged in and rotating with the bowl. The lighter liquid flows into the chamber 2 through a central opening 3, communicating with the inner part of the separating chamber 4 of the bowl. From the outer part of the separating chamber channels 5 extend to the upper edge of the bowl neck above the chamber 2 and are partly closed at the top by an exchangeable annular regulating disc 7, from the rim 8 of which the liquid is thrown into a collecting chamber, not shown, in the hood of the bowl.

The chamber 2 is located in that member which separates the separating chamber from the channels 5. As shown in the figure, the lower wall 11 may be removably secured to the rest of chamber 2. The paring disc 1 may, if desired, be provided with a number of vertical channels 12, crossing the outlet channels for liquid. The channels 12 are positioned inside the level of liquid and are provided for the purpose of obtaining a communication for the air between the upper and lower side of the disc.

15 The channels for liquid provided in the paring disc 1 communicate with a channel 13 positioned in a cover which, in known manner, is tiltably arranged above and covering the bowl. This cover also contains a supply channel 14. The two channels 13 and 14 can both be coupled to fixed pipe lines through the hinge of the cover, in known manner.

20 Referring to Fig. 2, which shows a modified type of outlet, the lighter liquid flows into the chamber 2 through a plurality of openings 3' in the member 11', which openings are desirably positioned sufficiently near the bowl axis to form a level outlet for the lighter liquid, so that its 25 free surface in the parer chamber 2 has a greater radius than in the chamber 4. The channels 5' lead from the outer part of the separating chamber 4 to a chamber 6 positioned above the chamber 2 and bounded at the top by an upwardly 30 dished regulating disc 7', from the rim 8' of which the heavier liquid is thrown into a collecting chamber formed by the hood 9 covering the separator bowl, and a lid 10 provided thereabove.

35 In the construction shown in Fig. 1, if the lighter liquid should overflow the chamber 2 it would discharge into the collecting chamber for the heavier liquid and be mixed therewith. This contingency is prevented by the structure shown 40 in Fig. 2, where the upper wall of the chamber 2 is provided with an upwardly projecting neck 15, over which any overflow from the chamber 2 is discharged into a special collecting chamber, not shown.

45 In the bottom of the bowl 4 drain channels 16 are provided, the inner orifices of which are ordinarily situated inside the level of the liquid, but which act as overflow channels when the sludge space of the bowl is filled with solid matter which clogs the normal path of flow through the bowl.

50 In Fig. 1 a device for lifting the upper and inner parts of the bowl out of the bottom of the bowl is shown in dotted lines. The device sub- 55

stantially consists of an arm 17 which, in known manner, is axially movable and is provided with a screw 18, which is screwed into a thread 19 in the central part of the bowl, the screw being introduced through the inlet tube 20 which is built integrally with the paring disc 1. The arm 17 is provided with a downwardly projecting skirt 21, which rests on the upper portion of the bowl and guides it in relation to the arm 17.

10 What I claim and desire to protect by Letters Patent is:

15 A centrifugal separator comprising a bowl having an upwardly extending neck portion and, extending inwardly therefrom, members forming the upper and lower walls of a lighter liquid parer chamber, a stationary paring device extending into said parer chamber, there being an opening in the lower of said walls communicat-

ing with the inner zone of the bowl and through which the lighter liquid separated in the bowl chamber is adapted to flow into the parer chamber, said opening being positioned substantially nearer the bowl axis than the receiving opening of the paring device and forming a level outlet for the said liquid so that the free surface of said liquid in the bowl chamber has a lesser radius than in the parer chamber, there being a channel for heavier separated liquid communicating with the outer zone of the bowl and located in said neck portion and extending to an open space above the parer chamber, and an exchangeable regulating disc extending from said neck portion inwardly above said space and forming a level outlet for the heavier separated liquid. 10 15
